MAIL BAG LOCK

Edward E. Joy, Wichita, Kans., assignor of one-third to Peter Q. Nyce, Washington, D. C., and one-third to Robert T. Smith, Caldwell, Kans.

Application January 20, 1934, Serial No. 707,924

5 Claims. (Cl. 70—2)

The invention relates to mail bag locks, and more particularly to an attachment whereby an ordinary Government lock may be permanently secured to the swinging member of the hasp type fastener commonly in use in the United States Mail Service.

According to present standard practice the draw strings or cords of the mail bags are provided with fastening devices of the hasp type which in the released position may be freely slid along the draw cords of the mail sack, while in the secured position the fastener is firmly clamped to the draw cords. In this manner the mail bag may be secured in closed position.

According to present practice a lock separate from the fastener is employed for retaining the clamp or fastener in the gripping position.

The standard equipment referred to above is generally very satisfactory in operation so far as securing the mail bag is concerned, but is subject to the serious disadvantage that the lock frequently becomes separated from the mail pouch and is lost, so that the mail bag becomes useless until a new lock is obtained.

Mail bag locking means have been proposed which include a lock forming an integral part of a mail bag fastener, but such locking means are in general complicated and involve a departure from standard mail service equipment.

According to my invention the standard U. S. mail bag fastener may be employed together with the standard U. S. mail lock, the improvement residing in the permanent attachment of the lock to the swinging member of the standard hasp fastener.

Preferably the improved attachment comprises a plate which is permanently secured as by electrical spot welding or the like to one face of the Government lock, the plate being provided with means for permanent attachment to the swinging member of the standard cord gripping fasteners, in such a manner as to permit a limited sliding movement of the lock upon said swinging member until the key is turned in the lock. When the device is locked the swinging member is secured in fixed relation to the other member of the fastener and the device as a whole is retained in gripping position upon the draw cords until the key is again turned, enabling the swinging member to be again released.

The invention will be more readily understood by reference to the accompanying drawing in which is shown an illustrative embodiment of the invention.

In the drawing,

Fig. 1 is a perspective view of the assembled device including a standard fastener of the swinging hasp type, the swinging member of the fastener being equipped with a standard lock permanently but slidably connected thereto;

Fig. 2 is a side view of the same, the full lines indicating the swinging member in the cord clamping or gripping position, and the dotted lines showing the swinging member in the released position;

Fig. 3 is a top plan view showing the fastener in gripping position, and the lock proper locked to prevent unauthorized releasing of the fastening means;

Fig. 4 is a top plan view of the device, showing the fastener in gripping position, but the lock proper unlocked, a portion of the fastener being broken away;

Fig. 5 is an under side view showing the swinging member of the fastener with a plate secured thereto, which plate is employed for connecting the lock to the fastener, and

Fig. 6 is an exploded view of the members shown in Fig. 5.

Referring to the drawing in detail, A designates the draw strings of a standard mail bag and B designates a fastening means of the swinging hasp type which now forms part of the standard Government equipment. The fastening means includes a relatively fixed portion X which may be clamped to the cords and a relatively swinging portion Y. The lock proper C, which may be standard Government equipment, is permanently connected to the swinging member Y of the fastener B in such a manner as to permit limited lengthwise movement when unlocked.

The fixed portion of the fastener B includes a base plate 10 provided with downwardly and inwardly turned flanges 11, which are adapted to receive a suitable identification tag (not shown) in accordance with the usual practice. The numeral 12 indicates a cord guide provided with a partition 13 dividing the same into two sections to separate the draw cords. One end of the cord guide is higher than the other. A second cord guide 14 is secured at the other end of the base plate. Between the cord guides 12 and 14 an upright plate or tongue 15 is secured as by welding or the like to the base plate. The upright plate 15 is provided with a reduced end portion 16, which projects into the larger end of the cord guide 12, the top of which is slotted to receive the end 16. Beneath the projection 55

16 is an open space 17 within which one end of the swinging hasp member Y is movable. The upright plate 15 is provided with lateral projections 18, 18 carrying guide rollers or fulcrum members 19, 19. Adjacent the end of the plate opposite from the tongue 16 is an opening 20 for receiving the locking jaw of the lock member, in a manner to be hereinafter described. Except when the swinging hasp member Y is in clamping position, the member X of the fastener is adapted to be moved freely along the cords. In closing the mail bag the fastener will be moved close to the bag and the cords A drawn to pucker and close the mouth of the bag. When the bag is to be opened the fastener will be slid away from the bag in the usual manner.

The relatively swinging member Y of the fastener comprises a plate-like lever arm 21 including a flat portion 22 at one end having an elongated slot 23 adapted to pass over the vertical plate 15. The flat portion of the swinging member is cut away on opposite sides, as at 24, 24, forming shoulders 25, 25 and 26, 26 at the ends of the cut-away portions. The elongated slot 23 merges at one end into an enlarged portion 27 of rectangular shape. The end of the swinging member opposite the flattened portion is bent downwardly at 28 and upwardly at 29, and terminates in a reduced tongue 30 adapted to fit into the enlarged open end of the cord guide or keeper 12.

The hasp or swinging member Y is permanently but swingingly attached to the fixed member X. The slots 23 and 27 permit the swinging member to be slipped over the nose 6 of the upright plate, which is afterward permanently secured to the base plate as previously described. When the swinging member is in the raised or dotted line position, the cords A, A pass loosely over the end 30 of the swinging member and through the slot 27 on opposite sides of the upright plate 15, thence rearwardly through guide 14. When the swinging member is lowered, the cords are clamped by the tongue 30 against the top of the guide 12, leverage being obtained by engagement of the surface 31 at one edge of the slot 27 against the rollers 19, 19. The fastening member above described may be and preferably is standard Government equipment.

According to the present invention a lock C may be spot welded or otherwise permanently secured to an attaching plate 32, shown reversed in Figs. 5 and 6. At the edges the attaching plate is provided with downwardly and inwardly turned flanges 33 adapted to slide upon the enlarged rear portion 34 of the swinging member of the fastener B. The attaching plate is also provided with a slot 35 which is adapted to register with the slot 23 in the swinging member. The sliding movement of the plate with the attached lock is limited by inturned lugs 36, which are adapted to engage shoulders 25 of slot 24 at one position and shoulders 26 at the other limit of movement. The amount of this movement will be dependent upon the length of the slots 24 and the size of the lugs 36, which, as will be noted, may be formed by cutting away portions at the ends of flanges 33 and bending the same toward the body of the attaching plate. Any suitable means may be employed for permanently securing the lock to the attaching plate 32. Spot welding may be employed, or a steel band may be used for connecting the plate and lock, such band being suitably secured both to the lock and the plate.

The lock, when opened, is adapted to be snapped fast by moving the lock and the plate to which it is attached a short distance in the direction of the arrow from the position shown in Fig. 4 to that indicated in Fig. 3, in which position the lock will be retained until released by a key inserted in the key hole 36'. The lock employed is preferably the standard lock employed in the United States Mail Service, the operation of which is well known and need not be described in detail. In the illustrative embodiment herein shown a key-actuated member 37 is pivoted at 38 to the housing of the lock and is provided with a key-engaging portion 39 and an arm 40 adapted to engage the hole 20 in the plate 15. A cam surface 41 on the member 37 is adapted to be engaged by one end of the upright plate 15 when the lock is moved in the direction of the arrow (Fig. 4) in snapping the same shut. A suitable spring 42 may be employed to hold the key-actuated member 37 in the desired position. The parts described are diagrammatic in character and are intended to illustrate an operative structure, but it will be understood that a standard Government lock is intended to be employed.

The automatic snapping shut of the lock is permitted by reason of the limited movement of the attaching plate 32 on which the lock is carried. Since this plate is permanently secured to the swinging portion of the fastener member, the lock cannot be separated from the fastener and become lost.

The present device possesses the important merit in that it does not require material modification of existing equipment. The attachment is cheap to apply and its operation is extremely efficient.

While the device has been described with particular reference to a mail bag lock, it will be understood that in its broadest features it is of more general application and the principles may be applied to bag locks of other kinds.

What I claim is:

1. The combination with a mail bag fastener having a staple carried thereby and a mail bag lock, of attaching means for permanently securing the lock to a portion of said fastener, said attaching means comprising a plate to which the lock is rigidly and permanently secured, and having flanges slidably fitting over a portion of said bag fastener, together with stops for limiting the sliding movement, said plate being centrally slotted to permit passage of said staple.

2. The combination with the swinging hasp of a fastening member having a central slot adapted to pass over a fixed staple carried by the fastening member, and having recessed portions at opposite sides of the slot parallel thereto and terminating in shoulders short of the ends thereof; of a lock having means adapted to engage said staple when in locked position, and means for permanently securing the lock to said hasp, comprising a plate to which the lock is secured and adapted for limited sliding movement upon the hasp member, said securing means having a central slot corresponding with the slot of said hasp, and having guide flanges slidably fitting over the edges of said hasp, together with stops for limiting the sliding movement of said carrier plate by engagement with the shoulders at opposite ends of the recessed portions of said hasp.

3. The combination with a movable plate-like hasp member of a fastening device having a central slot adapted to pass over a fixed staple carried by the fastening device, and having cut-away portions at the sides thereof parallel to but terminating in shoulders intermediate the ends of the slot, of a lock carrier plate permanently mounted for limited sliding movement on said hasp member, said carrier plate having a central slot corresponding with the slot of said hasp member and having stops for limiting the sliding movement of said carrier plate in either direction by engagement with the shoulders at opposite ends of the cut-away portions of said hasp.

4. In combination with a mail bag fastener including a member adapted to slide upon the draw cords of the mail bag, said member carry-

ing a staple, a swinging member adapted to clamp the cords within the fastener and having a slotted portion to pass over said staple; a lock for engagement with said staple carrying a plate permanently secured to the swinging clamping member but having limited sliding movement with reference thereto when in unlocked position, said plate being centrally slotted to permit passage to and from the staple.

5. In combination, a mail bag fastener carrying a staple, a mail bag lock for engagement with said staple, and an attaching plate permanently securing the lock to a portion of said fastener, said attaching plate having a slot to permit passage of said staple and to permit sliding movement of the lock when snapping the same shut.

EDWARD E. JOY.
